[57] **CLAIM**

The ornamental design for a disk drive front panel or
similar article, substantially as shown and described.

DESCRIPTION

FIG. 1 is a front elevational view of a disk drive front panel or similar article showing my new design;
FIG. 2 is a plan view thereof from the top;
FIG. 3 is a plan view thereof from the bottom;
FIG. 4 is an elevational view thereof from the rear;
FIG. 5 is an elevational view thereof from the left side;
FIG. 6 is an elevational view thereof from the right side;

FIG. 7 is a perspective view of the disk drive front panel of FIGS. 1-6 showing the panel's interlocking knob in its unlocked position, and also showing in phantom line a disk about to be inserted; and

FIG. 8 is a second perspective view generally similar to FIG. 7 but showing the interlocking knob rotated to its locked position, and also showing in phantom line the disk already inserted.
